(57) **CLAIM**

We claim the ornamental design for a “countertop drinking water system with cover”, as shown and described.

DESCRIPTION

FIG. 1 is a right front top perspective view of the “countertop drinking water system with cover” according to the present invention;

FIG. 2 is a left front top perspective view of the “countertop drinking water system with cover” according to the present invention;

FIG. 3 is a right front bottom perspective view of the “countertop drinking water system with cover” according to the present invention;

FIG. 4 is a left front bottom perspective view of the “countertop drinking water system with cover” according to the present invention;

FIG. 5 is a front view of the “countertop drinking water system with cover” according to the present invention;

FIG. 6 is a rear view of the “countertop drinking water system with cover” according to the present invention;

FIG. 7 is a right side view of the “countertop drinking water system with cover” according to the present invention;

FIG. 8 is a left side view of the “countertop drinking water system with cover” according to the present invention;

FIG. 9 is a top view of the “countertop drinking water system with cover” according to the present invention; and,

FIG. 10 is a bottom view of the “countertop drinking water system with cover” according to the present invention.
